UNITED STATES PATENT OFFICE

159,209

AIR CONDITIONING UNIT

Frederick M. Jones, Minneapolis, Minn., assignor
to The U. S. Thermo Control Co., Minneapolis,
Minn., a corporation of Minnesota

Application June 7, 1948, Serial No. 146,816

Term of patent 14 years

(Cl. D62—4)

To all whom it may concern:

Be it known that I, Frederick M. Jones, a citizen of the United States of America, residing at Minneapolis, in the county of Hennepin and State of Minnesota, have invented a new, original, and ornamental Design for an Air Conditioning Unit, of which the following is a specification; reference being had to the accompanying drawing, forming part thereof.

Fig. 1 is a perspective view showing the front, top, and one side of an air conditioning unit embodying my new design;

Fig. 2 is an elevational view of the side shown in Fig. 1;

Fig. 3 is a front elevational view of the unit; and

Fig. 4 is an elevational view of the side opposite that shown in Figs. 1 and 2.

The dominant features of my design reside in the portions shown in full lines.

I claim:

The ornamental design for an air conditioning unit, as shown and described.

FREDERICK M. JONES.
